UNITED STATES PATENT OFFICE.

DAVID LESTER, OF LOCKPORT, NEW YORK, ASSIGNOR OF ONE-HALF TO
BENJAMIN F. SCHAD, OF SAME PLACE.

DESIGN FOR A STOVE-GRADE.

SPECIFICATION forming part of Design No. 33,922, dated January 15, 1901.

Application filed December 13, 1900. Serial No. 39,788. Term of patent 14 years.

To all whom it may concern:

Be it known that I, DAVID LESTER, a citizen of the United States, residing at Lockport, in the county of Niagara and State of New York, have invented and produced a certain new and original Design for a Stove-Grate; and I do declare the following to be a full, clear, and exact description of the invention, such as will enable others skilled in the art to which it appertains to make and use the same.

This invention relates to a new and original design for stove-grates; and it consists of the design and configuration shown in the accompanying drawings, in which—

Figure 1 is a perspective view, and Fig. 2 is a longitudinal sectional view.

The leading features of the design consist

of an approximately rectangular open-work frame composed of parallel bars 1 and cross-bars 2, the hooks 3 at the four corners of the frame, and the handle-loop 4 projecting upwardly from the frame at approximately its center.

What I claim, and desire to secure by Letters Patent, is—

The design for a stove-grate as herein shown and described.

In testimony whereof I have hereunto set my hand in presence of two subscribing witnesses.

DAVID LESTER.
